BUTTON MAKING

George E. Pfeiffer, North Arlington, N. J., assignor
to Kreibiel Engineering Corporation, New York,
N. Y.

Application August 18, 1938, Serial No. 225,622

3 Claims. (Cl. 79—11)

This invention refers to an improved method of and means for making buttons. More particularly it refers to the operation of perforating buttons, and to the performance of other operations in connection therewith.

Buttons are known in which the perforations are connected by a kerf upon the surface of the buttons, such kerfs serving to receive and accommodate one or more threads slung from one perforation to the other.

At times kerfs are rendered elaborate, in which case they are commonly termed "fisheyes." Such "fisheyes" do not only serve the purpose of the kerfs but they may also be decorative, flaring beyond the perforations to be interconnected thereby.

Fisheyes were heretofore superimposed upon buttons by separate milling or furrowing operations, which followed the drilling of the perforations in the buttons. The button was chucked for such a furrowing operation, the previously provided perforations assisting in the alignment of the button in the position in which it was to be furrowed. Then a revolving grinding wheel or milling cutter was lowered onto the chucked button and cut the fisheye, the shape of which corresponded therefore in cross-section to a segment of the grinding wheel or milling cutter.

Such operations are cumbersome, and it has been an object of this invention to provide a fisheye upon a button while it is mounted for other operations thereon, or to combine the drilling of holes or perforations in a button with the cutting of a fisheye, or with similar operations.

It has been another object of this invention to overlap the cutting of the fisheye with other operations performed upon the button so that this operation does not require any extra time.

It is a further object of this invention to convert the operation of cutting a fisheye in a button in such fashion, that the operation of perforating the button may be expedited and simplified.

Buttons are ordinarily made of condensation products or brittle material, which are not particularly adapted for mechanical operation. When that is the case or when it is desirable to perform operations quickly, edges and corners frequently chip off the buttons during manufacture. This occurs particularly in connection with the drilling of the perforations of a button, for instance as a drill breaks through when emerging on the opposite side of a button. For that reason it even has been found to be expedient, to go through the cumbersome procedure

of drilling a perforation in a button from opposite sides, i. e. about half-way from one side and half-way from the opposite side, so that a hole does not "break through" the surface of a button and a chipping of the surface is avoided.

It has been a particular object of this invention to prevent a drill which bores perforations in a button from "breaking through," without having recourse to cumbersome operations serving to prevent chipping, like the double-drilling operation just referred to.

These and other objects of this invention will be more clearly understood from the following description thereof. For the purpose of illustrating the invention, a particular button-making machine is described herein in detail. It will however be understood by those versed in this art, that the method and means of this invention may readily be incorporated and embodied in other button-making machinery.

In the drawings:

Fig. 1 shows a button drilling machine, partly in elevation, partly in cross-section.

Fig. 2 shows a composite of cams which are schematically superimposed upon each other in order to illustrate how the method of this invention can be performed automatically.

Fig. 3 shows the top view of a button, which is perforated and provided with a fisheye.

Fig. 4 shows a modification of a button in a similar top view, a pair of fisheyes being here applied in cross-formation.

Fig. 5 shows a cross-sectioned side view corresponding to the button of Fig. 3.

Fig. 6 shows a cross-section of the same button, this cross-section being taken in a direction normal to the cross-section of Fig. 5.

Figs. 7 and 8 are the end and side views, respectively, of a drill.

Fig. 9 is the side view of a drill serving as a mill.

Figs. 10 and 11 are schematic cross sections which illustrate, respectively, consecutive stages of a combined fisheye cutting and drilling operation.

Similar numerals refer to similar parts throughout the various views:

A stock 11 arises substantially centrally from the bed 12 of the machine shown in Fig. 1. The button blank 13 is fed from above and circumferentially engaged by a suitable chuck in stock 11. The faces of the chucked button blank 13 are substantially fully exposed, so that they are faced by the drill head 14 to the right and the drill head 15 to the left, respectively.

To the rear of the machine is arranged a worm shaft 16, which carries on its end a step pulley 17. The drill spindles 18 are preferably supported with end thrust in the drill heads 14 and 15, and they respectively carry pulleys 19. These pulleys, like the step pulley 17, may be connected by suitable belt drives to a counter shaft (not shown). Worm shaft 16 drives the cam shafts 21 and 22 by worm wheels 20, one of said shafts being arranged to the left, and the other one to the right of the machine. Superimposed upon the machine is a magazine 23 for button blanks. It contains a hopper 24, which is driven from cam shaft 21 by way of a worm drive 25 and a chain drive 26 with take-up idler 27. The button blanks are guided from the hopper by way of chute 28, the feed mechanism 29 being controlled from a cam on cam shaft 21 by way of a lever 30, whereas the chucking is controlled by a cam (not shown) on the other cam shaft 22. The feeding and chucking proceed in the manner known in this art; and these operations are not explained in detail because no claim is laid thereto.

In the embodiment shown in the drawings, a button blank 13 remains stationary in the stock 11, while the operations now to be discussed are performed thereon. The mills or drills 31 or 32 are removably mounted at the end of the drill heads 14 and 15. While actuated by the belt drives they rotate continuously around an angularly substantially fixed axis; but they are each controlled for movement in all directions. The two drill heads 14 and 15 are substantially symmetrical to each other in respect to arrangement for such control. But for the method of this invention, drill head 14 with drill 31 is equipped for movement of milling a fisheye, whereas drill head 15 with drill 32 is moved to drill perforations in the button blanks.

In the case of drills 31 and 32, a control of movement in all directions is obtained by synthesizing it from an endwise, a transverse and a vertical component, each of these components involving, in the case of each of the drill heads 14 and 15, a separate cam control. Strictly speaking the endwise components involve reciprocatory movement in an endwise direction; whereas the transverse and vertical components involve oscillatory movement. But in connection with the last two components, the far ends of the drill heads serve as fulcra; and since the arcs of movement of the tools 31 and 32 in a transverse and a vertical direction are very short, they both virtually reciprocate in moving in a transverse or vertical direction.

Manufacture of a button like that shown in Fig. 3 involves the use of the endwise component and either the vertical or the transverse component, the former alternative being here shown and described in detail. On the drill head 14 to the right, which is shown to be equipped for cutting fisheyes, we use on cam shaft 22 the cam RE (right endwise) and cam RV (right vertical). On the left drill head 15 an endwise and vertical component of the operation of drilling the perforations of the button blank are obtained by the cam LE (left endwise) and cam LV (left vertical), respectively.

On the cam shaft 21, on which are mounted the last mentioned cams, the drawings also show a cam LT (left transverse), to which would correspond a cam RT (right transverse) in a symmetrical arrangement on cam shaft 22, which latter cam RT is not shown. The cams RT and

LT may replace the cams RV and LV in making a button like that shown in Fig. 3. Or they may come into play in adding the horizontal fisheye 33 shown in connection with the perforations 34 and 35 on button 36 of Fig. 4 to the vertical fisheye 37 and perforations 38 and 39 of the button 40 of Fig. 3.

Except for the cams and tools used the arrangement of the drill heads is substantially the same to the left and to the right, as follows:

Since all cams are shown as face cams, it is presumed that the respective rollers are tensioned thereonto, e. g. by springs. Plates 41 are endwise slidably mounted in the bed 12 of the button making machine, each one of these plates, to the right and to the left of the machine, carrying a roller 42, which engage upon the cams RE and LE, respectively. From the corners of bed 12 arise posts 43, a pair at the left end and a pair at the right end. Between a pair of these posts a swing plate 45 is fulcrumed upon a pivot 44 connecting the tops of said posts 43. The swing plate 45 depends, at its lower end 46, into engagement with the plate 41, so that the swing plate 45 is swung back and forth as the plate 41 is reciprocated by cam RE or LE. Each swing plate 45 is provided with a vertical row of tapped holes 47. In any one of these holes 47 may be mounted the set screw 48, the free end of the set screw protruding from the plate to a distance set by way of a nut locking the set screw 48 upon the plate 45. The assemblies of drill heads 14 or 15, are pushed, e. g. by springs 49, into abutting engagement upon the free ends of the set screws 48. According to whether the set screw 48 is mounted higher or lower in one or the other of the tapped holes 47 of swing plate 45, the rise or drop of cams RE and LE, respectively, is transmitted to the drill head assembly by way of the respective screw 48 at a more or less reduced fraction.

Each drill assembly is arranged as follows: Each assembly has a base 51, which is slidably superimposed upon the plate 41, and which may be slid endwise as well as transversely upon the bed 12, being retained thereon by flat top rails 52. By tension means (not shown) similar to spring 49 base 51 is tensioned towards the observer of Fig. 1; e. g. it is aligned along the front extent of bed 12, except where the drill end of said base 51 is pushed away from the front of bed 12 by the free end of a set screw 53 abutting thereupon. Set screw 53 is mounted in the free end of the lever 54, which is fulcrumed by way of a bracket 55 upon the bed 12 of the machine, and which is engaged by way of a roller 56 at its other end upon a cam RT (not shown) or LT, respectively. Thus the end of a base 51 extending towards the stock 11, will be pushed in an oscillatory movement by the set screw 53, when the lever 54 is rocked by the respective transverse cam on the respective cam shaft 21 or 22.

From opposite ends of each base 51 arise the forked brackets 56 and 57. By way of screw pivots 58 the far ends of one of the drill heads (14 or 15) are fulcrumed in the forked brackets 56, and the free drill ends of said drill heads are vertically slidably guided by the parallel inner faces of the legs of the other forked brackets 57. Set screws 48 engage upon the backs of forked brackets 56, so that the drill heads 14 and 15 are endwise moved by the cams RE and LE. By way of cam RT (not shown), and LT a transverse movement of the tools 31 and 32 at the front end of drill heads 14 and 15 may be gov-

erned. Tools 31 and 32 are raised and lowered by the cams LV and RV. The transmission gearing for this last control movement comprises a lever 59 fulcrumed upon bed 12 and carrying at one end a roller 60 engaged upon the respective vertical cam RV or LV, and engaging at its other end 61 underneath the adjustable, vertically movable table 62, the far end of the drill head 14 or 15 resting upon table 62 for instance by way of a roller 63. Springs 64 serve to strap the drill heads 14 and 15 down.

Flat drills with round shafts, as they may be used for operating on buttons made of condensation products, for instance, are shown in Figs. 7, 8 and 9. The width of drill 32 between the substantially parallel cutting edges 68 determines the diameter of the perforations produced in the button blank, and the length of said parallel cutting edges depends upon the depth to which the perforations or holes must be bored until they merge with the fisheye as explained herein-after.

From the said parallel cutting edges 68 the drill converges to a point 66; and it widens out at chamfer edges 67 for the purpose of producing a countersink at the entrance of a perforation, if so desired. The angle between the cutting edges 68 of the wider drill or cutting-tool 31 of Fig. 9 substantially corresponds to the desired angle between the converging sides of a fisheye 33 or 37.

In order to produce a fisheye upon the face of a button, a rotary tool like that of Fig. 9 is fed, as a rotating stylus, normally to its axis of rotation, past the top face of a button. While thus fed past the button, the tool is first axially advanced and then axially withdrawn from cutting engagement with the button, thus producing a furrow in the button.

Let us assume that the operation just described is being performed on the button of Fig. 3, the milling or furrowing tool moving vertically up. Simultaneously with the operation of advancing the furrowing or milling tool, while it moves up uniformly, hole 38 is drilled in the button from the back, this drilling operation being substantially finished and the drilling tool being withdrawn, when the furrowing or milling tool has arrived, in its upward movement, substantially at the center of button 40 (Position A). Now the perforation 39 is drilled from the back of the button, while the milling or furrowing tool continues from the center of the button in its upward movement, the milling or furrowing tool being at the same time slowly withdrawn, e. g. conversely to the way it had been previously advanced. The milling or furrowing tool will emerge from the top or front surface of the button substantially when perforation or hole 39 has been drilled and that drill has been withdrawn from the back of the button (Position B).

The drill does not have to bore from the back through the button 40, when providing the perforations 38. Even if the drill has extended only partly into the button from the back, in boring said perforation, the perforation will be laid bare, as shown in Fig. 3, when the milling or boring tool passes thereover in its upward progress.

If a drill like that shown in Fig. 8 is used, the distance from the corners between the parallel edges 65 and chamfering edges 67 to the tip of the drill should therefore be less than the thickness of the button to be perforated. The drill will then be inserted for producing perforation 38, until the cutting edges 68 begin to provide

a chamfer in the back of perforation 38. Then the drill 32 is withdrawn, although it has not yet emerged from the front of the button. The drill should also be extended from the back of the button for substantially the distance just described, when a perforation 39 is drilled. In that case the drill will break through into the lower portion of fisheye 37, which then has already been produced. But there is no danger of a chipping of the button material, when the drill thus breaks through, because of the slanted position of the fisheye walls.

That operation is illustrated by Figs. 10 and 11. Fig. 10 illustrates a stage of operation just before the aforementioned position A has been reached. As compared with said position A Fig. 10 shows that the drill has not yet been withdrawn and that the fisheye milling tool has not yet reached the center of the button.

Similarly Fig. 11 shows a stage just preceding position B. The drill again has not yet been withdrawn and the end mill furrowing the fisheye has not yet emerged from the surface of the button.

From the start, i. e. after a button blank 40 has been fixedly mounted in position, the rotating drills 31 and 32 move along a path respectively indicated by a solid arrow, until they reach, serving respectively as an end mill and as a drill and countersink tool, the position of Fig. 10.

Similar arrows in connection with Fig. 11 show the movement of the drill from the position of Fig. 10 to that of Fig. 11.

From the position of Fig. 11 the drills return to a position of rest, or a starting position, by following the dash-lines leading up to the beginning of the solid arrows of Fig. 10; then the button 40 is replaced by another blank.

In order to carry out the method just described automatically, a button making machine, for instance that of Fig. 1, is fed and chucked cyclically with button blanks in the position 13 shown. Drills like those of Figs. 9 and 8 are mounted in the drill heads 14 and 15, respectively, and the following order and arrangement of cams is used for producing a button like that of Fig. 3. No transverse movement is used, e. g. cam LT is not required; therefore the two drill heads will remain aligned in a vertical plane, which extends substantially through the center of the button and through the axes of the drill heads.

The cams LE, LV, RE and RV, have been angularly coordinated in the systematic view of Fig. 2, so that they represent a chronological order of operations, when they revolve in clockwise direction and all cam rollers apply upon one and the same line through the center. At the upper left corner of Fig. 2 we have the discharging, feeding and chucking interval, during which a finished button is dropped and a new button blank is fed and set into the position 13. Such intervals may be more particularly defined by the angular extent of the concave section of the cam surface RE, the remaining section of said cam being for instance eccentrically circular with an apex at 71, i. e. just opposite the lowest point of its concave section. Cam RE (right endwise) which is indicated in a solid outline in Fig. 2, will therefore impart between chucking operations, first a slow movement to the left, and then a corresponding slow movement to the right, to the milling tool 31 of drill head 14, these movements corresponding to the

advance and withdrawal motion of the description of the method given above.

The dot-dash surface of cam RV (right vertical) describes a true spiral curve between chucking intervals, so that table 62 and therefore also milling tool 31 rise at a uniform speed past the front of button blank 13, this movement corresponding to the vertical upward movement past the front of the button in the method described above. During this uniform upward motion of tool 31, it cuts the fisheye 37 into the button blank. Said fisheye gapes in cross-section corresponding to the angle between the cutting edges of tool 31, and the shape being determined as to depth and length by the horizontal level at which the set screw 48 is mounted in one or the other of the tapped holes 47, and by the extent to which said set screw 48 extends beyond the respective swing plate 45. During the chucking interval, when tool 31 is withdrawn from the button blank position 13 by virtue of the concave portion of cam RE, the milling tool 31 returns to its lowest starting position, by way of the quick drop 72 of cam RV.

The two cams just described are mounted on cam shaft 22. Cam LV, which is mounted upon cam shaft 21, is indicated in a dash line merging with the outer circumference of the cam hub 13 for a low dwell. To said low dwell corresponds on the opposite side a high dwell 74, said dwells corresponding in reference to the drill 32 in drill head 15 to the levels of the perforations 38 and 39 to be bored in the button blank 13. Thus the drill 32 is in the raised position of dwell 74 after the chucking operation, at which level it may drill a hole 38. For a similar period of the next cutting operation, the low dwell of cam LV holds the drill 32 in a position for boring the perforation 39. To these two dwells of cam LV correspond two uniform, truly spiral rises, 75 and 76, of the cam LV (left endwise) which is shown in the drawing in a solid double line. In other words, during chucking intervals the perforations 38 and 39 are successively bored. The perforation 38 is bored while the milling tool 31 furrows the bottom half of the button. When the latter has reached the center of the button, the boring perforation 38 has substantially been finished. Then the tool 31 continues past the center over hole 38, laying it bare toward the surface of the buttons as a perforation. During this latter period the perforation 39 is drilled, tool 32 now being in a bottom position, corresponding to the bottom dwell of cam LV.

A similar button, in which the fisheye and the perforations are horizontally aligned, will be obtained when the drill heads are moved transversely instead of being moved vertically, such action being brought about by the cams LT and RT (not shown), which then are provided with

faces corresponding to those of the cams LV and RV, respectively. Therefore a party acquainted with cam gearing will readily understand that a drilling and furrowing like that shown in Fig. 3 may also be followed in the same cycle by a drilling and milling in the horizontal direction, so that a button of Fig. 4 is produced.

Having thus described my invention in detail, yet I do not wish to be limited thereby, except as the state of the art and the appended claims may require, for it is obvious that various modifications and changes may be made in the form of embodiment of my invention, without departing from the spirit and scope thereof.

What I claim is:

1. Making a button, comprising a first step of milling a fisheye through the surface of one side of a button blank by moving the cutting point provided at the end of a rotary cutting tool across the surface of said side of the button blank, the axis of rotation of said cutting remaining substantially normal to said surface, and advancing and then withdrawing said tool into the body of the button blank while it is thus moved across, pierces said surface at a slant, furrows through said body and finally emerges at a slant from said surface, and a second step of providing a hole in said blank by drilling from the opposite side of the blank through the blank into the fisheye being milled into said one side after the milling of the fisheye has been started and before such milling has been finished.

2. Making a button, comprising drilling a hole into one side of a button blank, withdrawing the drilling tool, milling a fisheye into the other side of the blank starting from a point removed from the axis of said hole but moving towards said axis, said fisheye merging with and being milled across said hole after withdrawal of the drilling tool therefrom, moving the drilling tool counter to the direction of the cutting of the fisheye, and then again drilling with the drilling tool into said one side of the blank until the hole produced merges with said fisheye.

3. Making a button, comprising drilling a hole into one side of a button blank, withdrawing the drilling tool, milling a fisheye into the other side of the blank starting from a point removed from the axis of said hole but moving towards said axis, said fisheye merging with and being milled across said hole after withdrawal of the drilling tool therefrom, moving the drilling tool counter to the direction of the cutting of the fisheye, and then again drilling with the drilling tool into said one side of the blank until the hole produced merges with said fisheye, said milling operation being continuous and chronologically substantially coextensive with said drilling operations.
